(57) **CLAIM**

The ornamental design for an electric elliptical trainer, as shown and described.

DESCRIPTION

FIG. 1 is a front elevational view of an electric elliptical trainer showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a front perspective view thereof.

1 Claim, 7 Drawing Sheets
